(57) **CLAIM**

The ornamental design for an insulin carrying case, as shown and described.

DESCRIPTION

FIG. 1 is a top perspective view of the handy insulin case including a top sleeve and a bottom sleeve in accordance with one embodiment of the present invention;

FIG. 2 is a front elevational view of the insulin carrying case of FIG. 1;

FIG. 3 is a right side elevational view of the insulin carrying case of FIG. 1;

FIG. 4 is a bottom plan view of the insulin carrying case of FIG. 1;

FIG. 5 is a rear elevational view of the insulin carrying case of FIG. 1;

FIG. 6 is a top plan view of the insulin carrying case of FIG. 1;

FIG. 7 is top plan of an alternative embodiment of a bottom sleeve associated with the insulin carrying case of FIG. 1;

FIG. 8 is a front elevational view in accordance with the embodiment illustrated in FIG. 7;

FIG. 9 is a right side elevational view in accordance with the embodiment illustrated in FIG. 7;

FIG. 10 is a rear elevational view in accordance with the embodiment illustrated in FIG. 7; and,

FIG. 11 is a bottom plan view in accordance with the embodiment illustrated in FIG. 7.

Portions of FIGS. 1-11 are shown in dashed lines for illustrative purposes only and form no part of the claimed design.
